CLAIM

The ornamental design for a seat cushion for an infant, substantially as shown and described.

DESCRIPTION

FIG. 1 is a perspective view of a seat cushion for an infant;

FIG. 2 is a front elevational view of the infant cool seat of the invention;

FIG. 3 is a rear elevational view of the infant cool seat;

FIG. 4 is a side elevational view of the infant cool seat viewed from one side; the side elevational view of the infant cool seat from the opposite side is a mirror image;

FIG. 5 is a top view of the infant cool seat; and

FIG. 6 is a bottom view of the infant cool invention.
